UNITED STATES PATENT OFFICE.

FREDERIC L. THOMPSON, OF NEW BEDFORD, MASSACHUSETTS, ASSIGNOR TO
THE PAIRPOINT MANUFACTURING COMPANY, OF SAME PLACE.

DESIGN FOR A METALLIC PATTERN-STRIP.

SPECIFICATION forming part of Design No. 22,736, dated August 22, 1893.

Application filed March 31, 1893. Serial No. 468,569. Term of patent 7 years.

To all whom it may concern:

Be it known that I, FREDERIC L. THOMPSON, a citizen of the United States, residing at New Bedford, in the county of Bristol and State of Massachusetts, have invented and produced a new and original Design for a Metallic Pattern-Strip, of which the following is a specification, reference being had to the accompanying drawing, showing my new design.

The leading feature of my design consists in full blossoms and half blossoms combined with scrolls, as more fully set forth herein.

B is the pattern which is cast, molded or otherwise placed on or worked into various articles of manufacture which it is desired to

decorate, and in this ornamental pattern b is a full blossom which is followed by a scroll b', which is followed by a half blossom b², which is followed by a scroll b³, next to which is a full blossom b⁴ partially surrounded by a scroll b⁵ after which comes a full blossom b⁶ followed by a scroll b⁷ having oval openings, after which comes a compound scroll b⁸.

What I claim is—

The design for a metallic pattern strip herein shown and described.

FREDERIC L. THOMPSON.
